UNITED STATES PATENT OFFICE.

GEORGE P. FARMER, OF MONTCLAIR, NEW JERSEY.

DESIGN FOR A HAIR-PIN.

SPECIFICATION forming part of Design No. 22,642, dated July 25, 1893.

Application filed June 8, 1893. Serial No. 477,017. Term of patent 14 years.

To all whom it may concern:

Be it known that I, GEORGE P. FARMER, of Montclair, in the county of Essex and State of New Jersey, have invented and produced a new and useful Design for Hair-Pins; and I do hereby declare that the following is a full and exact description thereof, reference being had to the accompanying drawing, and to the letters of reference marked thereon, making a part of this specification.

My invention relates to hair-pins of the style generally used by ladies in securing the braids or coils of their hair in position, and its object is to produce a highly ornamental and useful design.

The figure of the accompanying drawing presents a perspective view of a hair-fastener embodying my design.

The special features of the design are the circular or substantially circular head *a*, and the sharp inward bends *b*, *b*, forming a neck immediately below the head, and the shoulders *c*, *c*, the prongs *c*, *c*, being more widely separated than the inner portions of the bends.

I claim as my invention—

The design for a hair-pin, substantially as herein shown and described.

In testimony whereof I have signed my name to this specification in the presence of two subscribing witnesses.

GEORGE P. FARMER.

Witnesses:

A. N. JESBERA,
A. WIDDER.
